UNITED STATES PATENT OFFICE.

PAUL SCHEUNCHEN FERDY, OF SAN FRANCISCO, CALIFORNIA.

MUSTACHE-SHAPER.

SPECIFICATION forming part of Letters Patent No. 587,193, dated July 27, 1897.

Application filed February 24, 1897. Serial No. 624,761. (No model.)

To all whom it may concern:

Be it known that I, PAUL SCHEUNCHEN FERDY, of San Francisco, in the county of San Francisco and State of California, have 5 invented a new and Improved Mustache-Shaper, of which the following is a full, clear, and exact description.

This invention has for its object to provide means by which a mustache may be easily 10 and quickly shaped; and the invention consists in certain features of construction, which will be fully described hereinafter, and defined in the claim.

Reference is to be had to the accompanying 15 drawings, forming a part of this specification, in which similar characters of reference indicate corresponding parts in all the figures.

Figure 1 is a view showing the invention in use. Fig. 2 is an elevation of the invention 20 with parts broken away, and Fig. 3 is a sectional view on the line 3 3 of Fig. 2.

The invention consists in a band of flexible material having two layers *a* and *a'* stitched together at the center of the band on lines *b* 25 and having at each end an elastic loop *c*. The loops *c* are secured to the ends of the band by passing the loops between folds in the sheets *a* and *a'*.

In using the invention the mustache is 30 dampened and the band placed over the mus-

tache, as shown in Fig. 1. The loops *c* are then respectively engaged with the ears of the person using the device, so that the band will be pressed firmly against the mustache to hold the latter spread against the face of 35 the person using the mustache-shaper. This will shape the mustache very properly and in a manner which will cause the mustache to retain its shape for a comparatively long time. 40

Having thus described my invention, I claim as new and desire to secure by Letters Patent—

A mustache - shaper consisting in a flat 45 flexible band formed of two layers of material, the ends of which are turned in and stitched together, and an elastic loop at each end of the band, each loop being passed between the end portions of the material and having one portion lying snugly against the 50 inner faces of the layers and the elastic loops projecting from the band at the side edges thereof whereby the bands are held open to readily engage the ears of the person using the mustache-shaper.

PAUL SCHEUNCHEN FERDY.
